H. C. EGERTON.
TELEPHONE RECEIVER.
APPLICATION FILED OCT. 5, 1912.

1,124,401.

Patented Jan. 12, 1915.

UNITED STATES PATENT OFFICE.

HENRY C. EGERTON, OF PASSAIC, NEW JERSEY, ASSIGNOR TO WESTERN ELECTRIC COMPANY, OF NEW YORK, N. Y., A CORPORATION OF ILLINOIS.

TELEPHONE-RECEIVER.

1,124,401.

Specification of Letters Patent.

Patented Jan. 12, 1915.

Application filed October 5, 1912. Serial No. 724,057.

To all whom it may concern:

Be it known that I, HENRY C. EGERTON, a citizen of the United States, residing at Passaic, in the county of Passaic and State 5 of New Jersey, have invented a certain new and useful Improvement in Telephone- 10 Receivers, of which the following is a full, clear, concise, and exact description.

This invention relates to telephonic receiving apparatus and more particularly to a telephonic receiving device of the type used for announcing and like purposes and commonly known as a load speaking receiver.

15 The object of this invention is to provide a new and improved device of this type of few and simple parts, rigid construction and improved operation.

Features of the invention are the means 20 provided for mounting the sound box, the means provided for obtaining the adjustment of the magnetic parts, the means by which the armature of the electromagnet is maintained in position without the use of 25 retaining springs or screws and other details of structure as will hereinafter more fully appear.

In the drawings illustrating this invention—Figure 1 is a longitudinal sectional view taken upon line 1—1 of Fig. 2; Fig. 2 is a view in front elevation with parts removed of a receiver embodying this invention; Fig. 3 is a detail perspective view of the armature and lever arm of the improved structure; Fig. 4 is a detail perspective view of the magnet coils and mounting and Fig. 5 is a detail sectional view taken upon line 5—5 of Fig. 2.

As shown in the drawings, 5 and 6 designate two members of a metal casing, the member 5 being formed integrally with a base or mounting portion 7 and the member 6 being formed separately and secured to the member 5 by means of machine screws 45 engaging lugs 8, 8 on said member 5.

Attached to the casing member 6 is a double horseshoe magnet comprising arms 9, 10, 11 and 12 all connected to a common yoke 13. The bars 9 and 10 are of the same 50 polarity as are also the bars 11 and 12, the latter two being of opposite polarity to the former two, the bars 9 and 11 being in one path of a complete magnetic circuit and the bars 10 and 12 being in a separate path

of a complete magnetic circuit. Extending 55 between the bars 9 and 11 and secured to the inner face thereof is a block 15 of brass or other non-magnetic material having a ridge 16 formed thereon and being cut away or recessed at its central longitudinal 60 portion as shown at 17, 17 in Fig. 4. The block 15 is rigidly secured to the bars 9 and 10 by means of machine screws 18, 18 extending through said bars and engaging screw-threaded openings in said block 15. 65 The ridge 16 of said block is rounded on its upper surface and provided at its central portion with a notch 19, the purpose of which will hereinafter more fully appear.

Interposed between the lower face of the 70 block 15 and the adjacent faces of the bars 9 and 10 is a strip 20 of magnetic material preferably Norway iron which is secured to said block 15 by means of machine screws 21, 21. The strip 20 is provided with up- 75 turned portions 22, 22 constituting cores or poles for magnet spools 23, 23 mounted thereon adjacent to the recessed portions of the brass block 15. Extending through the strip 20 at its central portion is a screw 25 80 which abuts at its inner end against the block 15 and is provided with a locking nut 26. The purpose of this screw is to obtain the adjustment of the magnetic parts as will 85 hereinafter appear.

The magnets 23, 23 control the movement of an armature 30 carrying a lever arm 31, one end of which is attached to said armature, the other end being attached to a diaphragm 32 mounted in a sound box 33. As 90 shown the armature 30 rests upon the ridge 16 of the brass block 15 with its opposite ends in juxtaposition to the cores or poles 22, 22 of the strip 20 and is provided on its under face with a projection 35 which engages in the opening or notch 19 of the ridge 16 to prevent the movement of said armature longitudinally of said block. The poles 22, 22 are normally ground off so that they will come even with the top of the ridge 16 100 when the strip 20 is flat against the block 15 and the poles are adjusted simultaneously with respect to the armature by the turning of the screw 25. The armature 30 having one face toward poles 9 and 10 of like 105 polarity and its other face toward poles 11 and 12 also of like polarity but of opposite polarity to the poles 9 and 10 will be re-

tained against its support by the magnetic attraction of the permanent magnet. This eliminates the use of screws and springs for securing the armature in place.

5 The sound box 33 comprises two members 40 and 41 between which the diaphragm 31 is clamped, tubular rubber rings being inserted between the diaphragm and the walls of the sound box 33. Extending through the 10 member 40 of the sound box 33 and attached thereto is a tubular member 45. This tubular member 45 which is screw-threaded throughout its length extends between the bars 9 and 10 of the permanent magnet and 15 through an opening in the casing member 6 to receive a supporting member 46 of a horn 47. Upon opposite sides of the bars 9 and 10 of the magnet are mounted nuts and washers 48, 48 and 49, 49 by means of which 20 the tubular member 45 is clamped rigidly upon the permanent magnet. A clamping nut 50 and washer 51 are mounted upon said tubular member 45 adjacent the outer face of the casing member 6. A tubular 25 member 55 similar to 45 is secured to the member 41 of the sound box 33 and extends outwardly between the bars 11 and 12 and through an opening in the casing member 5. The opening through which the tubular 30 member 55 passes is provided with a screw-threaded bushing 56 and a clamping nut and washers 57 and 58 are provided for securing said tubular member 55 with the casing member 5. A supporting member 59 carrying 35 a horn 60 is mounted upon the outer end of the tubular member 55. The tubular member 55 is provided with an opening 61 through which the arm 31 extends into engagement with the diaphragm 32.

40 Terminal clips 65, 65 are mounted upon the casing member 6. The casing member 6 is also provided with a groove 66 containing a felt ring 67 against which the margin of the casing member 5 bears when the casing 45 is assembled.

By forming the permanent magnet with four arms and mounting the energizing windings and sound box between these arms there is obtained a compact structure easily 50 manufactured at a reasonable cost and one which is efficient in its operation and which may be subjected to rough usage and sudden jars without affecting the adjustment of the parts. By the use of flat top pole pieces set 55 close together with a flat armature pivotally supported between them the arm connected with the diaphragm can be given sufficient movement with but slight movement of the armature, thus enabling the structure to 60 work with the minimum air gap between the armature and pole pieces. The magnetic path is further improved by the use of the integral core piece and the single adjusting screw for varying the relation of the cores to 65 the armature, thus providing a magnetic

path of minimum reluctance. The elimination of springs and screws for retaining the armature in its operative relation to the poles of the energizing magnet is also of considerable advantage since it eliminates the 70 weight and friction necessarily attendant upon the use of these parts and also simplifies the structure and the cost of production.

I claim:

1. In a telephone receiver, a permanent 75 magnet embracing a plurality of arms, magnetic cores supported upon arms of like polarity, energizing windings for said cores, an armature located between the arms of said permanent magnet and maintained in 80 operative position with respect to said cores by the magnetism of said permanent magnet and a diaphragm connected with said armature.

2. In a telephone receiver, a permanent 85 magnet comprising a plurality of arms, energizing windings, a diaphragm controlled by said energizing windings, a sound box for said diaphragm, a tubular member rigidly attached to and opening into said sound box 90 and means for adjustably securing said tubular member to arms of said permanent magnet.

3. In a telephone receiver, a permanent 95 magnet comprising a plurality of arms, a supporting block of non-magnetic material extending between arms of said permanent magnet of like polarity, cores of magnetic material carried by said supporting block, energizing windings carried by said cores, an armature pivotally supported upon said supporting block in operative relation to said cores, a diaphragm operatively connected with said armature and means for adjusting said cores simultaneously with respect to said armature.

4. In a telephone receiver, a permanent 110 magnet comprising a plurality of arms, a supporting block of non-magnetic material extending between arms of said permanent magnet of like polarity, a strip of magnetic material secured to said block, cores formed integrally with said strip, energizing windings carried by said cores, an armature pivotally supported upon said supporting block 115 in operative relation to said cores, a diaphragm operatively connected with said armature and means for springing said magnetic strip with respect to said supporting block whereby the relation of said cores and said armature may be varied.

5. In a telephone receiver, a permanent 125 magnet comprising a plurality of arms, a supporting block of non-magnetic material extending between arms of said permanent magnet, a strip of magnetic material secured to said block and extending between said arms, cores formed integrally with said strip, energizing windings carried by said cores, an armature pivotally supported upon 130

5 said supporting block in operative relation to said cores, a diaphragm operatively connected with said armature and an adjusting screw extending through said magnetic strip and engaging a face of said supporting block.

6. In a telephone receiver, a permanent magnet embracing a plurality of arms, a supporting block of non-magnetic material 10 mounted upon arms of said permanent magnet, magnetizing cores carried by said block, energizing windings mounted upon said cores, a ridge portion extending longitudinally of said supporting block between said 15 cores, a flat armature pivotally supported by said ridge in operative relation to said cores, means for preventing the movement of said armature longitudinally of said supporting block and a diaphragm operatively connected with said armature.

7. In a telephone receiver, a permanent magnet embracing a plurality of arms, a supporting block of non-magnetic material supported upon arms of said permanent 25 magnet, magnetic cores carried by said supporting block, energizing windings for said cores, a ridge having a curved bearing surface extending longitudinally of said supporting block between said cores, said ridge 30 being provided midway of its ends with a notch, an armature resting upon said ridge upon opposite sides of said notch, a projecting member attached to said armature and engaging said notch and a diaphragm operatively connected with said armature.

8. In a telephone receiver, a permanent magnet comprising a plurality of arms, magnetic cores supported between arms of said

permanent magnet, energizing windings on said cores, an armature pivotally supported 40 in operative relation to said cores, a diaphragm operatively connected with said armature, a sound box for said diaphragm, a casing for said permanent magnet, and sound conducting means supporting said 45 sound box between arms of said permanent magnet and supporting said permanent magnet in said casing.

9. In a telephone receiver, a permanent magnet comprising a plurality of parallel 50 arms, magnetic cores supported by arms of said permanent magnet, energizing windings for said cores, an armature pivotally supported in operative relation to said cores, a diaphragm operatively connected with said 55 armature, a sound box for said diaphragm located between the arms of said permanent magnet, a casing for said permanent magnet having an opening through one side thereof, a tubular member attached to said sound 60 box extending between arms of said permanent magnet and through said opening in said casing, means carried by said tubular member for adjustably securing it to arms of said permanent magnet, means also carried by said tubular member for securing it in said casing and horn attaching means carried by the outer end of said tubular member.

In witness whereof, I hereunto subscribe my name this third day of October A. D., 70 1912.

HENRY C. EGERTON.
